UNITED STATES PATENT OFFICE.

WILLIAM C. WILLIAMSON AND HALVOR O. FLADVAD, OF PHILADELPHIA, PENNSYLVANIA, ASSIGNORS TO SAID WILLIAMSON, GEORGE W. WILLIAMSON, AND JOHN D. WILLIAMSON, OF SAME PLACE.

STEAM STEERING MECHANISM.

SPECIFICATION forming part of Letters Patent No. 257,796, dated May 9, 1882.

Application filed January 25, 1882. (No model.)

To all whom it may concern:

Be it known that we, WILLIAM C. WILLIAMSON, a citizen of the United States, and HALVOR O. FLADVAD, of Sweden, both residing in the city and county of Philadelphia, and State of Pennsylvania, have invented new and useful Improvements in Steam Steering Mechanism for Ships, of which the following is a specification.

10 Our invention relates to starting, stopping, and reversing the rudder-moving engine by means of devices illustrated in the accompanying drawings, in which—

Figure 1 is a side elevation. Fig. 2 is a sectioned side elevation of Fig. 1, and Figs. 3 and 4 are machines which embrace the same general principles shown in Figs. 1 and 2, though they are somewhat changed in the construction and arrangement of their several parts.

20 A, Figs. 1 and 2, is the housing of the device, which controls the rudder-engine, on a frame, B, secured to the deck of a vessel. Turning in bearings of the housing is a shaft, C, having a hand-wheel, D, on its extension, and fitted with a screw-nut, E, which moves in guides *a* of the housing to preserve its right-line motion and prevent it from turning on or with the screw C. The ends of the guides limit the extent of its movement back and forth, by which means the throw of the engine-

30 valve is regulated. A screw-thread, *b*, is formed in the bottom edge of the nut for engaging with a worm, F, fitted loosely on a parallel shaft, G, of the same housing, with which it turns and slides along by means of a feather, *c*. A collar, *c'*, of the worm is embraced by the forked end *d* of a bent lever, H, on a fixed center, *e*. The other end *f* of the lever is in connection with the steam-engine reverse valve, link, or other reversing device through the medium of a rod, I. On an extension of the shaft G is a steering-wheel, J, which is belted to the pulley of the steering steam-engine. This same shaft also carries the drum K for 40 working the tiller-ropes L'. The steering-wheel J is auxiliary. Should the engine give out or become interrupted it can take its place by disconnecting it from the engine-pulley. The position of the bent lever H indicates that

the steam is shut off from the engine and it is at rest. By retracing the various parts it will be obvious that if the hand-wheel D is turned in any required direction—say that of the arrow *g*—rotary motion will be imparted to the screw C. The nut E will be screwed or moved along it, and, being in contact with the worm F, will move it in the same direction—the arrow *h*. The movement of the worm will be transmitted by the lever H and rod I to the steering reverse valve, link, or other reversing device, which will be proportionately opened and the engine moved in a consequent direction. The power exerted by the engine is transmitted by belting or other suitable means from its pulley-wheel to the steering-wheel J and the drum K. The rotation of the latter operates the ship's rudder by the intervening tiller-ropes L'. The drum K turns the shaft G and its loose worm F, which, being in gear with the nut E, gradually forces itself along the shaft until the bent lever H is brought into the position shown in Figs. 1 and 2, for closing the reverse-valve, when the engine stops until the hand-wheel D is again turned for shifting the position of the ship's rudder. The rotation of the hand-wheel D either way cannot move the nut E more than length of the guides *a*, which depends upon the extent of vibration to be given to the ship's rudder.

In the modification Fig. 3 the screw M is fixed 80 and immovable. The hand-wheel M', to which is attached the screw M², turns on and screws along the screw M. A forked end or collar, *i*, of a bent lever, M³, similar to the lever H, Figs. 1 and 2, embraces the screw M², by which motion is given to the engine-valve through the intervention of a connecting-rod, as shown at I, Figs. 1 and 2. A stop-nut, M⁴, limits the degree of motion of the lever M³.

In the modification Fig. 4 the hand-wheel 90 N turns a screw, N', in housings N². On the opposite end of this screw is another screw, having a regulating-nut, N³, in guides. The screw N' engages a toothed wheel, N⁴, on a sliding bar, N⁵. This wheel in turn engages 95 with a screw, N⁶. It will be readily seen that the motion given to the hand-wheel N causes the screw N' to turn the toothed wheel N⁴,

which, being in gear with the lower screw, N⁶, as a lever, slides the bar N⁵ in a consequent direction, and thus turns the bent lever N⁷, for starting the engine and operating the ship's rudder.

The working of the lever H is the same in all the figures illustrated and described. The nut E is operated by turning the wheel D. Its travel back and forth is limited to the length of the guides a, which must be commensurate with the swing or vibration of the rudder, so that when the nut is at either end of the guides the rudder is either hard-port or hard-starboard. The lever H, which takes its motion from the nut E through the worm F, has sufficient motion to cause the steering-engine to hard-port or hard-starboard the rudder. No matter how much power may be applied to the

wheel D, the nut E when at the end of guides will be stationary, and the rudder will, at the 20 limit of its vibration, either port or starboard.

We claim as our invention—

1. The combination, substantially as before set forth, of the hand-wheel D, screwed spindle C, nut E, moving in guides, screwed sleeve F, and the lever H.

2. The combination, substantially as before set forth, of the hand-wheel D, screwed spindle C, nut E, moving in guides, screwed sleeve F, lever H, and shaft G.

WILLIAM C. WILLIAMSON.
